UNITED STATES PATENT OFFICE.

EMMA J. WELLER, OF WATERBURY, CONNECTICUT.

HAT-PIN RETAINER.

SPECIFICATION forming part of Letters Patent No. 674,544, dated May 21, 1901.

Application filed January 22, 1901. Serial No. 44,244. (No model.)

To all whom it may concern:

Be it known that I, EMMA J. WELLER, a citizen of the United States, residing at Waterbury, in the county of New Haven and State 5 of Connecticut, have invented certain new and useful Improvements in a Combined Hat-Protector and Pin-Fastener; and I do hereby declare the following to be a full, clear, and exact description of the invention, such as 10 will enable others skilled in the art to which it appertains to make and use the same.

This invention relates to an improvement in a combined hat-protector and pin-fastener, and is embodied in the combination and arrangement of parts presently to be described, and defined in the claims.

The invention relates, more generally speaking, to a device which may be applied to a hat on the inside thereof and with which the end 20 of the usual hat-pin may engage. Heretofore in this particular art the use of a hat-pin passing through both sides of the hat not only damages the hat material, and especially on that side through which the pin projects, but 25 also by having the pin projecting it is more or less dangerous. To avoid this objection the present invention is designed.

While other devices have been suggested, such as cushions and perforated plates against 30 which the end of the pin may be projected and in which the same may be held, yet it has been found that such devices are more or less cumbersome and complicated and do not offer a very secure holding means for the pin.

35 My invention, more particularly speaking, consists of a device into which the point of the pin may be extended and will be held or clutched against outward movement, and which will also be provided with a non-penetrable surface against which the end of the 40 pin will strike and which prevents the pin from passing through the hat at that side.

In the drawings I have shown an embodiment of the invention, but desire it to be understood that various modifications and changes may be made without departing from the nature and principle thereof.

45 In the drawings, Figure 1 is a sectional view of the hat. Fig. 2 is a detailed view of the 50 combined fastener and protector. Fig. 3 is a detailed elevation of the same, and Fig. 4 is an edge view showing in dotted lines the posi-

tion of the fastener during the act of inserting the pin.

Referring more specifically to the drawings, 55 A designates a hat, which may be of felt or any other material. This hat is conveniently provided on the inside with a protecting-strip B, which may be conveniently of buckram, wire-cloth, or other penetrable material. 60

C designates a hat-pin.

Located on the opposite side of the interior of the hat is the combined protector and pin fastener or holder which consists conveniently of a strip of buckram or other stiff material 65 D, such as wire-cloth or the like, the same being tapered slightly and formed into a spiral at its free end, the opposite end being attached to the hat-body in any convenient manner. This strip has secured at its edges 70 reinforcing binding edging of wire c, which is preferably of spring wire or metal, for the purpose of retaining its shape after having been bent in a spiral shape, as shown. Immediately opposite the spiral portion of the strip 75 D adjacent the side of the hat is a protector-plate E, which may be of metal or other hard substance, such as leather, which will serve to prevent the end of the pin passing therethrough. The spiral or curved portion of the 80 strip D is located diametrically opposite the point in the opposite side of the hat through which the hat-pin is usually and naturally inserted, as shown in Fig. 1.

The protector and fastener D is conveniently incased in a covering F of any light material.

By the above construction it will be noticed that the use of heavy pads is avoided and a very light fastener and protector provided. 90

In operation the end of the pin coming in contact with the curved sides of the spiral portion of the protector has a tendency to cause the spiral portion to yield until the pin passes therethrough. In its passage it engages the inner portion of the spiral and in similar manner acts thereagainst until the same passes therethrough and engages the protecting-plate, which prevents a farther insertion. Owing to the spiral-spring nature 95 of the securer or pad D, as soon as the pin passes therethrough the spiral having been distorted will reset, and thereby form what may be properly termed a "clutching" ac-

tion against the sides of the pin, thus firmly holding the pin against accidental movement, but permitting it to be withdrawn when sufficient pressure is exerted.

5 It is to be understood that the material of which the fastener and protector is made may be varied and that the material itself may be of such a nature as to dispense with the spring-wire edging. The essential feature of 10 the invention in this particular is in a holder or fastener which will have a gripping or clutching tendency on the pin after the same has been inserted, the gripping tendency being derived from a curved body which is distorted during the insertion of the pin and tends to assume its normal position as soon as the pin has passed therethrough, as distinguished from the flexible rubber diaphragm or plain cushion onto which and through 15 which the end of the pin may pass.

While I have shown the holding portion of spiral shape, it is to be understood that any other desirable shape can be had and that by the use of the term "spiral" is comprehended 20 a curved spring structure wherein one or more parts of the holding material is positioned so that the pin will pass therethrough and deflect it from its normal position.

Having thus described the invention, what 25 is claimed as new, and desired to be secured by Letters Patent, is—

1. The combination with a hat of a pin-securer attached thereto comprising a curved 30 yieldable penetrable strip having a free end portion arranged to be deflected from its normal position when engaged by a pin, and to return to its normal position after the pin has 35 passed through.

2. The combination with a hat, of a pin-securer consisting of a strip of penetrable hold-

ing material having a securing portion and a free curved return portion adapted to move toward and from its normal position, substantially as described.

3. In a hat the combination with a side 45 thereof, of a pin-fastener located within the hat consisting of a holding-strip of penetrable material having a portion bent spirally and arranged to be engaged by the pin, substantially as described. 50

4. The combination with a hat, of a pin-fastener secured to and located within the same consisting of holding material having a free end bent to present two oppositely-arranged holding portions free to be moved by 55 and upon the insertion of a pin.

5. In combination with a hat of a pin-securer located within the hat consisting of a strip of holding material having a spirally-arranged penetrable portion and a non-penetrable portion opposite the spiral portion, 60 substantially as described.

6. The combination with a hat of a pin-securer located within the hat consisting of penetrable holding material having a portion 65 thereof bent into a spiral, a plate arranged adjacent the spiral and means for retaining the spiral shape, substantially as described.

7. In combination with a hat of a pin-faster and protector consisting of a strip of 70 holding material having wired edges and a portion formed into a spiral and a plate secured to the strip adjacent the spiral, substantially as described.

In testimony whereof I affix my signature 75 in presence of two witnesses.

EMMA J. WELLER.
